Application July 2, 1945, Serial No. 602,818

7 Claims. (Cl. 73—421.5)

1

This invention relates to sampling devices. In one of its more specific aspects, it relates to devices and methods for sampling of fluids. The design and construction of automatically operated equipment for sampling of fluids has yielded heretofore relatively costly and usually rather cumbersome and awkwardly operating equipment. We have found that the principle involved according to our invention may be applied to sampling devices for use in the composite sampling of either gaseous or liquid streams. Our invention has special application in the petroleum industry but may be used as well in chemical or other industries where liquids or gases are to be sampled, compositely, over periods of time.

One object of our invention is to provide apparatus and a method for sampling of streams of fluids while in transit.

Another object of our invention is to provide a method and apparatus which may be used for the taking of composite samples of either liquids or gases over rather long periods of time.

Still another object of our invention is to provide an apparatus for the composite sampling of gas streams at pressures less than atmospheric.

Still another object of our invention is to provide an apparatus for the composite sampling of gas streams at pressures greater than atmospheric pressures.

These and other objects and advantages will be apparent to those skilled in the art upon reference to the following detailed description and annexed drawing which respectively describes and illustrates preferred embodiments of our invention, and wherein Figure 1 illustrates an embodiment of our invention adapted for the sampling of hydrocarbon liquids which vaporize upon release of pressure.

Figure 2 illustrates an embodiment of our invention adapted for sampling streams of non-condensable gases or normally liquid streams under pressures greater than atmospheric.

Figure 3 illustrates an embodiment of our invention adapted for sampling streams of gases or liquids at pressures less than atmospheric pressure.

Referring to the drawing and specifically to Figure 1 numerals 11, 12 and 13 refer to motor valves, such as conventional diaphragm operated motor valves. The actual valve mechanisms 14 may be of a needle valve type or any other type adapted for use in small size (small diameter) equipment. The motor portions 15 may be of any suitable design such as the standard flexible diaphragm motor operated by fluid pressure, as

2

air pressure. The flexible diaphragms 16 are attached in conventional manner to valve stems 17 and by movement of the diaphragm members the valve stems and accordingly the needle closure portions 14 are opened or closed. These valves may be spring loaded, as by springs 18. As shown in the drawing, each spring 18 serves as a tension spring and is so adjusted as to hold the valve needle in a normally closed position.

10 Upon application of instrument air pressure to the under side of the diaphragms, the valve stems 17 are raised to open the valves to the flow of fluid, the springs 18 being accordingly subjected to somewhat greater tensions. When the instrument air pressure is released, the normal tension of the springs moves the valve needles into their normally closed position.

A "proportioning chamber" 19 is inserted to connect motor valves 11, 12 and 13 as illustrated in Figure 1. This proportioning chamber may be a standard pipe or copper tube T-fitting provided its inside or passageway volume is the volume required for the taking of predetermined size samples. Connections 21 which connect this proportioning chamber to the respective motor valves 11 and 12 should be as short as possible and of as small a bore as is practical with the desired sturdiness of construction. A tube 24 is attached to the outlet end of motor valve 12 to direct disposal of material not desired as sample.

20 A tube 22 connects the side arm outlet of the proportioning member 19 to the motor valve 13. From the delivery side of this latter valve is a sample tube 23 for conducting the sample from the sample taking apparatus to a sample container, not shown.

A timing apparatus 25 such as a time cycle controller is shown as a means for controlling the several motor valves according to predetermined time intervals. While this time cycle controller may be any type or kind of controller desired, it is obviously only necessary that it be capable of performing the desired operations in a satisfactory manner. By this, we mean that the controller may be electrically operated or it may be operated by a spring operated clock mechanism. A particular time cycle controller which we have used and found to be entirely satisfactory is one manufactured by the Hanlon Waters Company, and is mentioned herein merely as an example. The time cycle controller which we have used operates on a six hour cycle, but by repeating the six hour cycle as many times as desired a composite sample of any desired size or over any desired period of time may be taken.

Time cycle controllers, such as the one mentioned above, operate according to pins, placed in holes around the circumference of a rotating plate. Thus by inserting pins into these holes over certain time intervals said pins, upon rotation of the plate, cooperate with other mechanism of the controller to permit flow of "instrument air" to such control apparatus as the air operated motor valves 11, 12 and 13. Such time cycle controllers as the one hereinabove mentioned are standard industrial equipment and may be purchased from equipment dealers or directly from instrument manufacturers.

Instrument air from an air supply, not shown, comes by way of a line 27 and passes through an air pressure reducer or regulator 26 to reduce the air pressure to that required for operation of such motor valves. This regulator 26 also contains a strainer element for elimination of foreign material from the air previous to entrance into the cycle controller. Said cycle controller contains valves for transmitting air pressure from the inlet air line 27 to air control lines 28 and 29 and for closing off and exhausting air pressure from said lines 28 and 29.

Since motor valves 11 and 12 are intended to operate simultaneously, they are operated off the same air line 29 by running branch air lines 31 and 32 to said motor valves. Line 28 admits air only to motor valve 13. As shown in Figure 1, these several air service lines transmit air pressure to the under side of the motor valve diaphragm members 16 so that an increase of instrument air pressure on the underside of said diaphragms will operate to raise the diaphragms and accordingly open the valves to the flow of fluid to be sampled. Springs 18 are so adjusted in tension that upon release of air pressure on the diaphragms the several valves will be positively closed. It is not critical that said air pressure be transmitted to the under side of these diaphragms for opening the valves since it may be piped to the upper side of the diaphragms and operate to close the valves by compression of the springs 18.

In the operation of the modification of our invention shown in Figure 1 for the sampling of a liquid hydrocarbon, such as butane, which will completely vaporize at atmospheric pressure, the liquid hydrocarbon comes from its transfer line through a small diameter sample line 20 and enters motor valve 11. For taking a sample of butane the time cycle controller clock 25 operates to admit instrument air from air line 27 to air line 29 and thence into the two branch air lines 31 and 32. From these branch lines the air pressure is transmitted to the diaphragms of valve motors (11 and 12), which motors respond by opening their respective valves. Liquid butane then flows from line 20 through motor valve 11, tubes 21 and the proportioning chamber 19, motor valve 12 and through bleed off line 24 to such disposal as desired. The control clock holds these valves open for such a predetermined time as is thought necessary to flush out thoroughly any residual material, of course motor valve 13 remaining closed. When such flushing is complete, the cycle clock operates to permit closing of the valves 11 and 12 and accordingly there is retained in the proportioning chamber and connecting elements a measured volume of liquid butane.

Finally, the cycle controller admits air pressure by way of tube 28 to the motor valve 13 to open said valve. The liquid butane in the proportioning chamber then vaporizes and the vapors

pass through the valve 13 and are led to a sample collecting device 33. We have found that the sample vapors may be collected by displacement of brine from a container 34, as say, a 5-gallon bottle. Other liquids may be used for displacement purposes but we prefer to use a salt water brine since hydrocarbon gases are relatively insoluble in such a solution. In case a larger sample than 5 gallons is desired it is, of course, only necessary to use a larger bottle, and vice versa if a smaller sample is desired.

Several conditions of apparatus and operation may be varied for taking various sizes of samples, etc. For example, for taking a 24-hour composite sample of butane, the concentration of which does not vary appreciably, a sample each hour over said period might be sufficient. However, in case the composition of a stream being sampled varies considerably from time to time, it might be necessary to take composite samples each 15 minutes or each half hour in order to obtain a true average of a 24-hour run. To vary the periods of sampling it is only necessary to insert pins in the rotating disc of the time cycle controller at the proper time points, that is, for 15 minute, 30 minute or 1 hour operation. We have used a 6-hour time cycle controller for taking samples of butane each 15 minutes over a 24 hour period, thereby making the 24-hour sample a composite of 96 individual samples. The pins in the rotating disc are so inserted as to permit valves 11 and 12 to remain open for about one minute, during which time the previous sample is well flushed from line 20, valves 11 and 12 and the connecting parts. Valves 11 and 12 then close and valve 13 opens and remains open for about 5 minutes which time has been found ample for complete vaporization of the sample from the proportioning chamber 19 and transfer of the vaporized sample into the sample collecting bottle 34. At the end of such period valve 13 closes and the sampling apparatus then awaits the next sampling time as determined by the time cycle controller 25.

One of the critical points in our apparatus of Figure 1 is the volume of the proportioning chamber 19 and connecting parts. In case the volume of this chamber 19 were too large, then a 5-gallon sample bottle might become filled with butane vapors with two or three samples instead of 24 hourly samples over a 1-day operating period. The effective volume to be considered from this point of view is the total volume of the "proportioning chamber" portion of the apparatus and this includes the volumes of all members from the needle 14 in motor valve 11, tube 21, chamber 19, tube 21 (extended), to the needle 14 in motor valve 12, and tube 22 to the needle 14 in motor valve 13. Thus, twenty-four times this total volume of liquid when vaporized will be the volume of the gas sample collected. In order to collect a composite gas sample of reasonable size, say five or ten gallons, this total volume must be relatively small as will be obvious to a chemist. For this reason, we prefer to use small bore tubing for tubes 21 and 22 and these tubes should be as short as practical. In addition, the diameter of the hydrocarbon conduit through said motor valves must be relatively small. In making our apparatus of Figure 1, we determined by calculation the total liquid butane volume required for this "proportioning chamber portion" of the apparatus, and knowing the volumes of the motor valve conduits, tubes 21 and 22, then we obtained the volume of chamber 19 by difference.

This procedure will need to be followed for making our apparatus for sampling such hydrocarbons as butane, isobutane, the butenes, etc. taking into consideration the volume of composite sample to be taken, the total time period over which the sample is to be taken, and the frequency for taking the individual sample fractions. We have found that once an apparatus of this character is properly constructed that it requires no man power for operation and all the time needed is that required for changing sample bottles.

The apparatus may well be housed within a box or other container for protection. However, the brine tank and sample bottle need not be completely housed but may be arranged under a roof to afford protection against such elements as rain, hail, snow, etc.

The embodiment of our invention illustrated in Figure 2 of the drawing is adapted to sampling of noncondensable gases under pressure. The principles and main points of operation are similar to those above described in relation to use of apparatus of Figure 1. In the device of Figure 2, gas under pressure and to be sampled comes from a vessel to be sampled by way of a line 41, passes through a motor valve 42, and through a connecting tube 43 into a proportioning chamber 44. From this reservoir or proportioning chamber 44 the sample of gas passes through a connecting tube 45, a second motor valve 46, through a transfer tube 47 and thence into a sample bottle 48. As sample gas passes into the sample bottle, liquid which for our purpose may be a brine solution, is displaced and flows into a brine tank 50, the level of the brine solution being indicated by reference numeral 49. Instrument air from a source, not shown, comes through an air line 52, passes through a pressure reducer and strainer 53, and finally enters a time cycle controller 55. This controller is adapted for admitting and closing off instrument air to tubes 56 and 57 for the operation of diaphragms 60 and 62 of the respective diaphragm motor valves 42 and 46. Pressure gages 54, 58 and 59 indicate the instrument air pressures in these respective control lines. The motor valves 42 and 46 may well be of the same type as those described in relation to Figure 1 and contain valve needles 63 and 64, and tension springs 65 and 66.

In the operation of this embodiment of our invention, the time cycle controller is set to operate at quarter hour, half hour, or hour intervals as desired. Instrument air from line 52 passes through the cycle controller 55, air line 56 to the under side of diaphragm 60. Air pressure at this point opens the valve needle 63 against the tension of spring 65. Under these conditions gas to be sampled under pressure flows from line 41 into the proportioning chamber 44, of course, motor valve 46 remaining closed.

Valve 42 remains open for a sufficient period of time to permit pressure in the proportioning chamber 44 to become equal to that in sample line 41. This period of time, however, is relatively short since the volume of the proportioning chamber is rather small. The valve, however, is usually set to remain open the minimum length of time obtainable on the specific cycle controller used. When the proportioning chamber is fully pressurized, then valve 42 closes, and valve 46 then opens and permits expansion and flow of the expanded gas through the valve and sample tube 47 and into the sample bottle 48. The displacement liquid in tank 50 and in the bottle 48 is

usually a brine solution, since such a solution has a relatively small solubility for the hydrocarbon materials sampled.

After the gas has been transferred to the sample bottle and the pressure in the sample chamber 44 has dropped to approximately atmospheric, valve 46 closes. The apparatus then remains idle in this condition until time for taking another sample.

The critical point in this particular gas sampling apparatus (of Figure 2) is the size of the proportioning chamber 44. The size or volume of this chamber should be such that for sampling a gaseous material under a certain pressure, that the required number of time spaced individual samples will not yield a composite sample of volume greater than the volume of the sample bottle 48. It will be obvious that the greater the pressure of the gas being sampled, and the greater the number of samples taken over a period of time, the smaller the sample chamber may be. For utility of sampling apparatus, we have found it advisable to make provision for the proportioning chamber to be removable from the apparatus so that various size chambers may be inserted depending upon sample requirements.

The apparatus shown, diagrammatically, in Figure 3 is intended for sampling gas streams or normally liquid hydrocarbons at slight vacuum or at a pressure too low to displace brine from a sample bottle. This apparatus is similar in many respects to those of Figures 1 and 2, but differs mainly in that a Toepler pump is used as a means for transfer of the gas from the process line under slight vacuum to a sample bottle under atmospheric pressure.

Referring to the Figure 3, instrument air from an air line 70 passes through a time cycle controller mechanism 71 and thence through lines 72 and 79. This time cycle controller may be similar to those described hereinbefore or any other type desired, provided it is suitable for the purpose at hand. Four motor valves, 75, 76, 77 and 78, are also similar to those mentioned in relation to Figures 1 and 2. A Toepler type mercury pump 82 is used as the actual means for transferring the sample of gas from the process line, not shown, through sample tubes 89 and 90 into a gas sample bottle 91. This pump consists essentially of a mercury reservoir 83, a sample tube 84 and a mercury transfer tube 94. The top of the sample tube portion of the pump has an outlet for connection to a tube 86; the mercury reservoir is provided with an opening for connection to a pipe 85.

In the operation of this embodiment of our invention (Figure 3), the time cycle controller operates to admit instrument air from pipe 70 to tube 79 and thence to tube 80 and the diaphragm of motor valve 76, and to tube 81 and the diaphragm of motor valve 78. These two motor valves then are forced open against the tension of their respective tension springs. With valve 76 open, air from another source under about 10 pounds per square inch gage pressure enters through air line 87, passes through the valve 76, pipe 85 and into the upper portion of the mercury reservoir 83. This air pressure forces the mercury from the reservoir 83 through tube 94 into the sample tube 84 to displace a sample of gas previously taken, forcing it through tube 86, motor valve 78 and sample tube 90 into the sample bottle 91 thereby displacing an equivalent quantity of the brine solution.

The height to which the mercury rises in the

sample tube 84 may be controlled by the pressure of the air entering through tube 85 or by a float valve mechanism so arranged as to prevent the mercury from rising from the sample tube 84 into the sample outlet tube 95.

After the mercury has completely expelled all sample gas from tube 84, the air pressure is maintained on the mercury in vessel 83 until the time cycle controller operates to close motor valves 76 and 78. Following the closing of these two valves the cycle controller then operates to open valves 75 and 77. The opening of valve 75 releases the air pressure from the mercury reservoir by way of air lines 85 and 88, while the opening of valve 77 opens up the sample line to the hydrocarbon or other gas being sampled. Accordingly the release of air pressure from the reservoir 83 permits the mercury to flow from sample chamber 84 to the vessel 83 while at the same time sample chamber 84 is being filled with sample gas from tubes 86 and 89. After passage of sufficient time for the mercury levels in tube 94 and in reservoir 83 to become equalized, the cycle controller operates to close motor valves 75 and 77 and to open valves 76 and 78. The opening of valve 76 admits air pressure to the mercury in vessel 83 forcing the mercury up the tube 94 to displace the gas sample from tube 84, the sample passing out through tube 86, through the motor valve 78 and sample tube 90 to displace a small volume of brine from the sample container 91. This last operation completes an individual sampling cycle.

Time cycle controllers such as the Hanlon Waters time cycle controllers, which we have used and which we mention by way of example, are standard equipment and may be purchased from instrument manufacturers or dealers. Many different kinds and types of such equipment are on the market and a user may use his judgment in selecting the one most suitable for the problem at hand.

The cycle controller to be used in conjunction with our sampling apparatus should be easily adjustable for the particular sampling conditions and should permit some of the operational steps to take place rapidly to prevent air leakage, or loss of or contamination of sample, while other operational steps should be of relatively long duration. These latter steps are necessary to permit passage of sufficient time in order to be able to take samples at such intervals as $\frac{1}{2}$ to 1 hour. In addition, in case it is desired to take samples at short intervals, say from 5 to 15 minutes, the controllers should be so adaptable. As mentioned hereinbefore, an operator may select from among many controllers since there are rather large numbers on the market.

When using the embodiment of Figure 3 for sampling normally liquid hydrocarbons, it is usually not necessary to take as large a sample as five gallons even over a 24-hour period and accordingly a smaller sample bottle may be used. The sample chamber 84 for this service will then be made of size as to give a desired volume of composite sample over a desired period of time.

In like manner, the motor valves for use in our sampling apparatus may be selected from among many types of motor valves listed in manufacturers' catalogues. Among the many kinds or types of valves available we have found that "needle valves" are quite satisfactory. However, we do not wish to limit our invention in any way to the use of needle valves since other

valves are satisfactory as, for example, "plug type" valves. We have found, however, that when using needle valves in conjunction with fluid operated diaphragm motors that we can construct a sampling apparatus for a very reasonable cost as compared to costs when using other valves with the necessary operating and control equipment.

In relation to the embodiment of our invention illustrated by Figure 1 wherein a liquid sample is withdrawn, allowed to vaporize, then passed to a sample container as a gas, the volume of liquid involved is of importance. If, for example, a five-gallon sample of butane vapor is desired as a composite sample to be representative of a 24-hour period of operation, and the five-gallon sample is to be made up of 48 individual samples taken at 30 minute intervals, it is obvious that each of the 48 individual samples must be relatively small. By calculation, based on a liquid density of butane as 0.6, then 5 cubic inches of liquid butane will vaporize to give five gallons of butane vapor at 32° F. and 1 atmosphere pressure. Each half hour sample should be approximately 0.1 cubic inch of liquid butane. Based on this reasoning, it is obvious that the volume of one individual sample of butane taken by the apparatus (Figure 1) will be the volume between the seats of motor valves 11, 12 and 13, which volume includes one-half the fluid passageway in each of these valves, tubes 21 and 22, and proportioning chamber 19. Thus the summation of these several volumes should be approximately 0.1 cubic inch in order that 48 individual samples will give about 5 gallons vapor. In making up an apparatus of this embodiment, it is then necessary to use motor valves having very small diameter fluid passageways, connecting tubes 21 and 22 should also be small diameter copper tubing, for example, while the total volume may be adjusted by selection of a proper volume of the proportioning chamber 19. Such small diameter materials, as tubing and the like, are readily available, while small size motor valves might need have their fluid passageway diameter made smaller. In one instance, we have filled the passageways in $\frac{1}{4}$ inch motor valves with lead then drilled out a small diameter passageway on the liquid sample side of the needle.

For the embodiments of our invention illustrated by Figures 2 and 3, no special "small volume" apparatus is required since gases are being sampled and the samples retained as gas in each case.

The individual parts of each of the three samplers are relatively small, and we have found that each sampler can be assembled on a wooden or metal base approximately 2 feet square and the base set into a housing having a side hinged door. The brine tank and sample bottle may best be disposed outside and adjacent the apparatus "box."

In the embodiment of Figure 3 for sampling gases at less than atmospheric pressure, care must be taken that the mercury from vessel 83 is not forced over the top of sample vessel 84. As mentioned hereinbefore, this point may be controlled by maintaining a certain maximum air pressure on the air in air line 81, and for each maximum pressure there will be a certain and fixed height to which the mercury will be forced as measured by the difference in mercury levels in vessels 83 and 84. For example, 15 pounds will call for the "X" distance in Figure 3 to be about 30.6 inches, while 10 pound air will decrease this

distance to about 20 inches. If this air pressure from air inlet pipe 87 can be depended upon not to exceed certain pressures, a check valve will not be needed in the outlet tube 95. We would, however, recommend installation of such a valve in all installations as a matter of safety to assist in preventing loss of mercury.

In all cases, the volume of mercury in the reservoir 83 must cover the open outlet end of the tube 94 to prevent passage of air into the sample tube 84 with subsequent contamination of sample in the bottle 91.

Also, as mentioned hereinbefore, the sampling intervals, etc. may be changed at will merely by changing adjustments in the time cycle controller, and such adjustments are well understood by those who operate such equipment.

Materials of construction may be selected from among those commercially available and suitable for the particular purpose at hand. If non-corrosive and chemically inactive gases are being sampled, ordinary materials may be used. If, however, sampling of corrosive gases is to be done, materials of construction should be resistant to such corrosion.

In relation to the motor valves, we have found that the metal type diaphragms work well in these small valve motors. If other kinds of diaphragms are found suitable, they may be used in place of those which we mention. Even stop-cock type valves may be used, but since these require electric motors for opening and closing, and complicated relays and wiring, we have found our air-operated samplers as herein disclosed are by far the least expensive to construct, and are simple and efficient to operate and are essentially fool-proof, that is, they have operated for long periods of time without exhibiting mechanical difficulties or troubles.

It will be obvious to those skilled in the art that many alterations and modifications of our samplers may be made and yet remain within the intended spirit and scope of our invention.

What we claim is:

1. A fluid sampling system comprising in combination at least two valves connected by a proportioning chamber and providing fluid flow therethrough; a fluid sample inlet conduit connected to the open end of one of said valves; a gas sample collector vessel; a gas sample outlet conduit extending from the free end of one of said valves to said gas sample collector vessel; fluid actuated valve operating means in each said valve; conduit means extending between a source of pressurized-fluid and said valve operating means; and a controller in said conduit means, adapted to control the flow of said pressurized-fluid to said valve actuating means so as to alternately actuate said valve in the inlet to said proportioning chamber and said valve in the outlet end of said chamber.

2. The fluid sampling system of claim 1, wherein a third valve is connected to said proportioning chamber; a gas vent conduit is connected to the free end of said valve; and pressurized-

fluid conduits connect the actuating means of said third valve and said valve in the inlet to said proportioning chamber to the same source of pressurized-fluid from said controller.

5 3. The fluid sampling system of claim 1, wherein one pressurized-fluid conduit extends between said controller and said actuating means of the valve in the inlet of said proportioning chamber; and a second pressurized-fluid conduit extends between said controller and said valve actuating means in the valve in the outlet of said proportioning chamber.

10 4. The fluid sampling system of claim 3, wherein a pressurized-fluid actuated gas pump is provided in said proportioning chamber; and a third pressurized-fluid conduit extends between said pump and the same source of pressurized-fluid from said controller as said second pressurized-fluid conduit.

15 20 5. A fluid sampling system for sampling gas at atmospheric to slightly below atmospheric pressure comprising in combination a proportioning chamber having an inlet and an outlet; a first motor valve in said inlet of said proportioning chamber; a second motor valve in

25 said outlet of said proportioning chamber; a gas sample collector vessel; a first fluid conduit connecting said second motor valve and said gas sample collector vessel; a mercury displacement

30 fluid pump connected to said proportioning chamber; a pressurizing system for said fluid pump comprising a pressurized-fluid conduit connecting a pressurized-fluid source and said fluid pump, and at least one motor valve in said pressurized-fluid line; and means for operating said motor valves.

35 40 6. The fluid sampling system of claim 5, wherein in a time cycle controller is in operational communication with said means for operating said motor valves.

45 7. The fluid sampling system of claim 5, wherein a second fluid conduit connects a constant pressure compressed air source and an air flow time cycle controller; and said air flow controller is connected to said motor valves by additional fluid conduits.
